UNITED STATES PATENT OFFICE.

E. F. BARNES, OF BROOKLYN, NEW YORK.

IMPROVED SELF-ADJUSTING AND EMBOSSED TELEGRAPHIC MACHINE.

Specification forming part of Letters Patent No. 20,982, dated July 27, 1858.

To all whom it may concern:

Be it known that I, EDMUND F. BARNES, of the city of Brooklyn, county of Kings, and State of New York, have invented and applied to use certain new and useful improvements in telegraphic apparatus for transmitting and recording messages at a distance, and which, from its operation, may be designated as the "Self-Adjusting Embossing Telegraph;" and I do hereby declare that the following is a full, clear, and exact description of the same and of its operation, reference being had to the accompanying drawings, and to the letters of reference marked thereon, and making a part of this specification.

The nature and character of my invention consists in the arrangement and production of a telegraphic machine or instrument that is easily and readily adaptable to the purposes of telegraphing and producing printed letters or symbols, and which, from its simplicity and construction and the ease and certainty of its operation, can be used under disadvantageous circumstances, and when other instruments are comparatively inoperative, and which, from its feature of self-adjustment, renders its action almost wholly perfect and free from mistakes.

Figure 1 is a front perspective view of the machine, some portions being broken away in part to more clearly exhibit the parts behind. Fig. 2 is a perspective view from behind. Fig. 3 is a representation of the gearing of the several parts. Fig. 4 is a detached view of the swing-frame. Fig. 5 is a view of the pedestal and the fly or power wheel.

The key-board A is semicircular in shape, and the keys *a* passing through it are arranged, as to the letters marked upon them, in the order in which such letters occur oftenest in telegraphic language. Such keys are also each fitted with a spiral spring, 1, so that as soon as any pressure is removed from them they will rise to their natural position.

Underneath the key-board A is a swing-frame, B, hung on points or pivots 2 2, under the back side of the key-board, and which is pressed down, as each key is touched, by a shoulder of the key striking against it. To this swing-frame is also connected, through the cross-bar 3 and bars 31 32, Fig. 4, and arm *c*, a forked bar, *b*, which extends under the clutch-wheel *g* for the uses hereinafter mentioned.

C is a hollow shaft, to which is attached the circuit-breaker arm *d*, which is of such a length that in revolving the end of it will come in contact with any key which may be depressed and be arrested. To this hollow shaft is also fixed the clutch *f*, and within such shaft *C* is a shaft, *e*, which bears the movable or sliding clutch-wheel *g*. As a key *a* is depressed it presses against the swing-frame B and forces it downward and through the parts 3 31 32, and arm *c* causes the forked rod *b*, which moves on its center 4, to move the clutch-wheel *g* upward on the shaft *e* and into gear with the clutch *f*. As the clutch-wheel *g* is on the inner shaft, *e*, to which is attached the gear-wheel 1^a, Fig. 3, this shaft revolves without carrying the hollow shaft *C* and the parts connected thereto, so long as the clutch-wheel *g* and clutch *f* are not in contact; but whenever a key is touched and the wheel *g* thrown into contact with *f* the hollow shaft *C* is caused to revolve, carrying with it the circuit-breaker arm *d*; and such arm by means of the click *h*, working into the ratchet-wheel 5, carries the circuit-breaker wheel *D*, to which the wheel 5 is fastened. When the finger is lifted from the key the spiral spring 1 lifts it up from off the swing-frame, and the spring 6 throws up such swing-frame, and the clutch-wheel *g* is released from gear with the clutch *f*, and the shaft *C* ceases to revolve, and the arm *d* is drawn to its original position or starting-point by the action of the spring, and cord *k*, which winds around the shaft *C*.

The circuit-breaker wheel *D* is circular, and has its periphery undulated (as shown in Fig. 1) in such a manner that upon its being revolved the hammer *l* is alternately connected with and disconnected from the anvil *i*, which is on the insulated stool *E*. The end of the anvil *i* presses against a helical spring in the stool *E*, which allows the anvil to yield a little to the contact of the hammer, but is stiff enough to insure a perfect contact between the hammer and anvil. By this arrangement the main circuit is alternately broken and closed; a wire extending from the "mutator," when used, or from the main line and connecting with the anvil *i*. Now, if the main wire be extended to any distant point and there connected with another of the telegraphic instruments, the main circuit will be connected when

the hammer *l* and the anvil *i* are brought in contact, and be discontinued when they are separated.

G is a resident magnet, the metallic cores *m* of which, within the coils, are composed of soft iron, with one or more straight-bar permanent magnets introduced into each leg of it and extending the length of the cores. The object of such permanent magnets is to keep at all times the atoms of the soft iron in a polarized condition, the poles of the small permanent magnets being so arranged as to produce north and south poles in the resident magnet, as it is found that without such arrangement there is considerable time lost in the charging and discharging the ordinary electro-magnet, and that by its use a much greater number of vibrations can be obtained in a given time. *H* is an armature over the resident magnet, which armature is composed or made up of several thin plates of soft iron, alternating with plates of brass or other non-conductor of magnetism, the greatest width of such plates being perpendicular with the length of the legs of the electro-magnet, and their number being sufficient to make the proper width of the armature.

J is a lever attached to the armature *H*, and suspended by points *7 8*. An adjusting screw, *k*, above, and another, *k'*, beneath, regulate the distance through which such armature may move.

L is an adjustable spring to cause the reverse motion or action of the armature *H* when the circuit is broken and the armature released from the attractive force of the resident magnet.

M is a screw by which the slide *N*, through which the spring *L* passes, may be moved to and fro, to vary the length of the working part of the spring. There is also a similar screw, *9*, underneath the slide *N*, by which it may be raised or depressed, as desired.

At the other end of the lever *J* is a small hardened-steel nipple, *n*, which comes alternately in contact with the teeth of and arrests the escapement-wheel *O* as the lever *J* is caused to vibrate by the attractive action of the resident magnet *G* on the armature *H* and the action of the spring *L* when the armature *H* is released from the attraction of the magnet. The escapement-wheel *O* is made by cutting two wheels with such a number of teeth on each as shall be equal to one-half the number of letters or characters used, and then fastening one of these wheels upon the other in such a manner that the teeth of one shall be equidistant between the teeth of the other, thus allowing the escapement-wheel *O* to revolve, step by step, at each vibration of the lever *J*.

P is a detent cog-wheel having on it a number of teeth equal to the number of all the teeth of the escapement-wheel *O*; and such wheel *P* is so arranged as to move up and down on a square shaft, *Q*, by the action of the forked bar *o* supported by the stud *p*.

R is the type-wheel, having on it a number

of letters corresponding with the number of teeth of the escapement-wheel *O*, on the under side of which type-wheel is a pin, *(.)*, (seen between letters *E* and *I*) which acts as a clutch to the detent-wheel *P* by passing between any two of the teeth of such wheel when it is thrown up to the under surface of the type-wheel by means of the forked bar *o*, but is withdrawn when by the action of the same bar, the wheel *P* is thrown downward, at which time, should the type-wheel have been carried forward any distance whatever, the action of the spring and cord *S*, which winds around the barrel of the type-wheel, will draw such type-wheel back until a pin, *10*, strikes against the stop *r*, when it will be at rest. This is accomplished by the type-wheel being loose and free to revolve on the type-wheel shaft *T*, except when the pin *(.)* underneath such wheel passes between the teeth of the detent wheel *P*, as before described.

U is a ratchet-wheel, having on it a number of teeth equal to those on the escapement-wheel *O*. On shaft *V* is an arm, *s*, one end of which rests upon one of the teeth of the ratchet-wheel *U*, and which is carried forward at every movement of such wheel *U*.

W is a detent fixed to the shaft *V*, and partaking of every movement of such shaft. On shaft *X* is an arm, *t*, which rests against the detent *W* at *u* until the ratchet-wheel *U* acts upon the arm *s* and partially revolves the shaft *V* and detent *W*, when the arm *t* will be released from the point or end *u* and move to and rest against the other end, *v*, of such detent *W* until the arm *s* shall have again fallen to the bottom of one of the teeth of the wheel *U*, when the arm *t* will be released from the end *v* of the detent *W*, and make a revolution till it again rests against such detent at *u*. On shaft *X* is also a cam, *w*, from which extends a rod, *z*, which acts upon the bar *Y*, Fig. 1, to move forward the imprinting-press *x* against the type-wheel *R*, such press and rod being forced back by the action of the band *a'*, against which such press acts, when the cam *w* has revolved sufficiently far to allow the end of the rod *z* to fall from off it at *xx*, Fig. 2. On the same shaft *X* are also the paper-propelling eccentric *y* and the type-wheel-releasing plane *b'*. From the paper-propelling eccentric *y*, a rod, *c'*, attached by a strap about such eccentric *y*, extends to one of the paper-rollers *Z*, which it causes to revolve a given distance at every revolution of the shaft *X* by means of the click *d'* working into the ratchet-wheel *e'* on such paper-roller. Such rod *c'* is guided and supported by a step and pins, *f'*.

Z are paper rollers or guides to draw and guide the paper as it passes between the press *x* and type-wheel *R*, and such rollers are held together for such purpose by means of the springs *l' l'*. The forked rod or bar *o* extends from the type-wheel-releasing plane *b'* to and takes hold of the detent cog-wheel *P*, forcing such wheel down at every revolution

of the shaft X, and again forcing it up when the arm t shall have passed so far around as to allow the end 1 of such rod o to drop from off the type-wheel-releasing plane b', such bar o being forced up by the spring 11. The type-wheel stop r arrests the type-wheel at each return, and is hung on a hinge, h', so that when the pin 10 on the type-wheel shall have made a complete revolution it forces such stop outwardly till the type-wheel commences to return, when the spring k' forces the stop r back to its proper position to arrest the type-wheel.

A A is the principal bed-plate to sustain the receiving portions of the instrument, and B' B' are posts to support the plate which receives the upper journals of the two shafts T and V and of the paper-rollers.

C' is the main power-shaft, driven by the foot, as shown in Fig. 5, or, as desired, having on it four cog-wheels to drive respectively the wheels on the type-wheel shaft T, the shaft V, and the shaft X, and also the wheel 1^a on the circuit-breaker shaft e.

The cog-wheels on all the shafts except the power-shaft, C' are loose and free to revolve on such shafts, having friction-plates above and below them fast to the shafts, so as to keep such wheels in position. On the power-shaft C' all the wheels thereon are fast except the wheel 1^b, which is caused to revolve by the friction-plate and box 1^c, and which wheel 1^b carries or moves the wheel 1^a. The wheel 1^a is connected with the clutch-wheel g by means of the cross-bar m', having at each end a pin, 12, which passes into corresponding sockets in the arms of the wheel 1^a. Such pins 12 move up and down in the arms of the wheel 1^a, so as to allow of the movement of the clutch-wheel g, as above described.

Any arrangement of friction-plates to keep the wheels in position, and allow them to revolve upon their shafts may made use of. The one in use is substantially as follows: About a shaft, as C', Fig. 3, is fixed a nut, o', the top of which is dishing, and in which sets the part p', which is fixed to the wheel 1^b. To the top of such wheel is fixed a friction-box, 1^c, in which works a friction-plate, o o, pressed down by springs n', which are confined by nuts n''. Between the friction-plate o o and the wheel is a piece of common leather, o', to lessen the friction. As the circuit-breaker arm d drops back to its proper place or starting-point a tail-piece, x', on the click h, that dips into the ratchet-wheel 5 below the circuit-breaker, comes in contact with an inclined plane, n', which raises the point of the click from out of the teeth of such ratchet-wheel, and prevents it from again dipping into such ratchet-wheel until the arm d has been carried a short distance forward. The object of this is to prevent the clutch f, by its sudden action when thrown into gear with the ratchet-wheel g, from throwing the arm d forward in improper time, and thus jumping over any letter.

The cog-wheels on the different shafts, except the circuit-breaker shaft, are so arranged, as before mentioned, that they may all be revolving while the shafts remain stationary, and their speed is so arranged that the circuit-breaker wheel revolves more rapidly than the wheel on shaft V. Supposing the wheels in motion, the general operation is as follows: When any key a is depressed the swing-frame acts upon the arm c and forked bar b, by which the clutch-wheel g is thrown upward and takes hold of the clutch f on the hollow shaft C, by means of which the circuit-breaker arm d and the circuit-breaker wheel D is revolved, alternately breaking and closing the circuit through the hammer l and anvil i, causing the lever j to vibrate, and allowing the shaft with the escapement-wheel o to move forward step by step, carrying with it the type-wheel R and ratchet-wheel U, until such time as the circuit-breaker arm d shall reach the depressed key, when such arm d will be arrested and the vibrations cease. At the first vibration the ratchet-wheel U forces or carries forward the arm s, moving with it the detent W, and allowing the arm t to pass from the point u of such detent to the point v, at which point v such arm t would rest until such vibrations cease, because the speed of the circuit-breaker wheel D being faster than that of the shaft V, the teeth of the ratchet-wheel U keep meeting the arm s, and prevent it from falling to the bottom of the teeth of U. As soon, however, as the arm d meets a depressed key, and the vibrations cease, and the type-wheel shaft stands at rest, the arm s is carried to the bottom of the tooth on the ratchet-wheel U, which revolves a little the shaft V and detent W, and releases the arm t from the point v, and the shaft X is revolved, imprinting the letter by the action of the cam w and rod z, which work the press x and immediately after the letter is so printed, and during the revolution of the shaft X, the type-wheel-releasing plane b' acts upon the forked bar or rod o, depressing the detent cog-wheel P and releasing the type-wheel, which is drawn back to its proper position or starting-point by the spring and cord S. At the same time, and during such revolution of the shaft X, the paper-propelling eccentric y, through the rods c' and click d', acting on the ratchet-wheel e' on the paper-roller Z, propels the paper far enough for the impression of the next letter, and as soon as the finger is taken from the key the clutch f is released from the clutch-wheel g, and the spring and cord k draw the circuit-breaker arm d to its original starting-point. By thus causing the circuit-breaker arm d and the type-wheel R to retreat to the same starting-point at the printing of each letter the machinery or instrument is self-adjusting, and that immediately after every letter is imprinted, and as this is done while the shaft X is revolving and the paper is being moved, no time is lost. The shafts T and X revolve in the direction indicated by

the arrow on the wheel U; but the shaft V revolves in the opposite direction, thereby causing the arm s to fall to the bottom of the teeth of U the moment such wheel is arrested. The spring within the insulated stool E, and against which the anvil i presses, should be sufficiently firm to cause a severe enough contact between the hammer and such anvil to overcome the effect of any oxidation that may be produced on their surfaces. The gearing to move the several parts is constructed in the ordinary manner, except as above mentioned and described, and may be worked by means of the foot on a treadle, as shown in Fig. 5, or may be moved by clock-work, or in any other manner, as convenient or desired.

In order to give the type-wheel shaft T and the type-wheel on it the necessary promptness and quickness of action whenever the vibration of the lever J releases the teeth of the escapement-wheel O, there is attached to the type-wheel shaft a box, r', Fig. 3, containing a coiled spring, one end of which is fastened to such box, and the other end fastened to the shaft. Above this is a friction-box, s', and its friction-plate, the particular arrangement of which is not more fully described here, as it is the invention of others, for which a separate application for a patent is to be made. The spring in the box r' is set up two or more turns, or as much as may be required to secure the desired prompt action to the shaft T, and is kept or held at such tension. Whenever the machine and gearing are set in motion the friction-plate, and the pressure of the spring s'' thereon, is sufficient to rotate the spring box r', and consequently wind up the spring therein to a certain point—usually half a turn—when it is arrested by the steel pin w' in the shaft T meeting the projection Y', after which the friction-plate and the pinion w' revolve about the shaft T. The moment the vibration of the lever J releases a tooth of the escapement O the spring will act upon and move the shaft T instantaneously, and the type-wheel is turned to the proper letter by the rotation of such shaft, and according to the pulsations given at the escapement O. This spring or an equivalent device is required, because of the great rapidity of the vibrations and the need of corresponding prompt action of the type-wheel shaft to prevent errors in imprinting. I am aware that a coiled spring has been used in a telegraph-machine (House's) to give action to a shaft; but it was not set up to and held at a given point, nor did the friction wind such spring only to a certain extent, but the friction alone set up or wound such spring, and to as great an extent as such friction would effect it; and, of course, when the machine was stopped the spring would entirely unwind. By setting up the spring to a given degree and there holding it, and then allowing the friction to wind such spring only a certain extent in addition, the spring has given it and always retains, the

necessary tension for the uses and purposes required.

The letters on the type-wheel are arranged in the order in which they occur oftenest in language used in telegraphing, whereby an average of a fraction less than seven vibrations are required to reach each letter, instead of an average number of vibrations equal to half the number of letters on the type-wheel, which would be required if the type-wheel made continuous revolutions without returning to a given starting-point at each letter.

The permanent magnets are introduced into the cores of the electro-magnet, because it is found that by causing the electro-magnets to be constantly polarized by the induced magnetism from the permanent magnets that the difficulty arising from the sluggish action of electricity in charging magnets, and the time necessary to discharge them, is overcome, since the compound magnet will vibrate with several times the rapidity of the ordinary electro-magnet with the soft-iron armature. For use of the instrument in the local circuit, and not in immediate connection with the main circuits, there is not, however, so much of a necessity of inserting the permanent magnets in the cores of the electro-magnet, as it is found by careful and repeated experiment that the formation, as above described, of the armature of alternate plates of conducting and non-conducting metals tends to insure a much more rapid vibration than could be obtained if the armature was entirely of soft iron, as a small mass or body of metal is much sooner magnetized than a larger mass and such construction of armature causes the entire number of iron plates to be magnetized as quickly as if there was but a single plate, or nearly so, because each plate is separate from each other conducting one. When, however, the instrument is to be used with the main circuits it will be advisable to have the permanent magnets inserted in the cores of the electro-magnet, as described. The use of such compound magnet also enables a much greater length of line to be operated than can be by the use of any other magnet, as it unites great sensitiveness with greater force than can be obtained from the simple electro-magnet.

In any printing telegraph-instrument in which the circuit-breaker and the type-wheel are not self-adjusting the two are often getting into different relative positions upon any two instruments, when operations must cease until they are adjusted together, which adjustment is almost absolutely necessary before the sending of any message; whereas by my invention these parts are self-adjusting, and are therefore always in the same relative position after the completion of every letter, and the operator has but to keep his magnet in adjustment, the other parts being self-regulating. The imprinting-cam, the paper-propelling eccentric, and the type-wheel-releasing plane are all

firmly attached to each other, thus rendering it impossible that they should get into different relative positions. The arrangement of the circuit-breaker is also such that the circuit is closed by a direct contact instead of a rolling or scraping contact, so that far greater certainty of vibration is secured and attained, and the whole instrument is so thoroughly adapted to its purpose in its mechanical construction and arrangement that the liability to disarrangement is very slight, while at the same time it is far simpler of operation than any character-instrument which depends upon the muscular action of the hand to form the characters.

I do not claim, generally, the use of the power of electricity or magnetism for telegraphing messages at a distance and recording them, either in printed letters or characters, nor the general arrangement of the wires, posts, or electric circuit or circuits, as these are old and well-known; but

What I specifically claim as my invention, and desire to secure by Letters Patent, is—

1. The use and application of the combined permanent and electro magnets in the resident magnet, substantially as and for the purposes set forth and described.

2. The arrangement of the springs *k* and *S* or their equivalent, in connection with the circuit-breaker shaft *C* and type-wheel shaft *T*, by which the circuit-breaker arm *d* and type-wheel *R* are caused to return to a given starting-point after the completion of each letter, thereby causing the instrument to be kept constantly self-regulated.

3. The use and arrangement or combination of the circuit-breaker wheel *D* with its undulated periphery, and the hammer *l* and anvil *i*, placed and arranged, substantially as described, so that the revolution of the wheel *D* shall alternately connect and disconnect such hammer and anvil, and also connected with the main battery and line, for the purpose of closing and breaking the main telegraphic circuit, substantially as set forth and described.

4. The arrangement, substantially as described, of the hollow shaft *C* and clutch *f* and arm *d*, and the connection therewith, substantially as set forth, of the spring-frame *B*, by which the clutch-wheel *g* is made to take hold of such clutch *f* on the hollow shaft *C* to carry forward such shaft *C* and the circuit-breaker, and the arm *d* whenever any key is depressed, substantially as set forth.

5. The arrangement and combination of the vibrating-lever *j* and its nipple *n* with the escapement-wheel *O*, constructed as described, to cause the type-wheel shaft to revolve, step by step, at every vibration of such lever, substantially as and for the purposes set forth.

6. The use and arrangement of the spring *L* with its adjusting-slide and adjusting-screws, substantially as set forth and described, for the purpose of regulating the action of the vibrating-lever *J*.

7. The arrangement and combination of the imprinting-cam *w*, the paper-propelling eccentric *y*, and the type-wheel-releasing plane *b'*, substantially as set forth, being attached to each other and placed upon a common shaft or otherwise, but so that it is impossible that they should get into different relative positions.

8. In connection with such imprinting-cam and paper-propelling eccentric and type-wheel-releasing plane, the arrangement and combination of the rod *z*, bar *Y*, and imprinting-press *x*, and the rod *c'*, and the rod *o*, which together cause the letter to be imprinted, the paper to be propelled far enough for the next letter, and the detent cog-wheel *P* to be forced down so that the type-wheel may return to its starting-point, and again forced up to clutch the type-wheel, and also cause each of these several things to be done at and in its proper time.

9. The arrangement of the armature *H*, constructed of alternate plates of conducting and non-conducting metals, when combined with an electro-magnet and used in connection with telegraphic instruments, for the purpose of securing a more rapid vibration of such armature.

10. The arrangement of the coiled spring, as described, about the type-wheel shaft *T*, such spring being set up to and held at a given tension, and such tension being increased only a certain amount by the friction, for the purpose of securing prompt action to such shaft, as described.

11. Generally, the arrangement and combination of the said several parts above described, substantially as and for the purposes set forth.

EDMUND F. BARNES.
